WRENCH

Charlie A. Graham, Apple Springs, Tex.

Application April 28, 1938, Serial No. 204,878

1 Claim. (Cl. 81—55)

This invention relates to a wrench set or combination and it particularly aims to provide a structure having all of the necessary sockets or heads, for use in connection with dual wheels of 5 Ford or other trucks, and for trailer wheels.

The invention resides in the novel combination of parts and details hereinafter described with relation to accompanying drawings illustrating an operative embodiment.

10 In said drawings:

Figure 1 is a view in elevation of the wrench set or assembly;

Figure 2 is a vertical section taken on the plane of line 2—2 of Figure 1;

15 Figure 3 is a view in substantially central vertical section through the set or assembly;

Figure 4 is a horizontal section taken substantially on the line 4—4 of Figure 3;

20 Figure 5 is a detail section taken on the line 5—5 of Figure 3;

Figure 6 is a detail section taken on the line 6—6 of Figure 3;

Figure 7 is an end elevation of the main tubular socket member, and

25 Figure 8 is a detail side elevation of the cup nut and collar nut connected together.

Referring specifically to the drawings wherein like reference characters designate like or similar parts, the invention employs an elongated tubular main socket member 10 whose walls are concentric interiorly and exteriorly except at a head 11 at one end, provided with a socket 12, preferably polygonal to fit a nut or the like.

30 Adjacent the other end of said main tubular socket member 10 an annular row of teeth 13 are provided and on opposite sides thereof parallel plates 14 are disposed which are rigidly bolted or otherwise fastened to an operating handle 15. A pawl 16, having opposite end portions 17, to co-act selectively with the teeth 13, as in a pawl and ratchet, to turn the socket member in either direction, is pivoted at 18 to a bolt spanning the plates 14. In order to hold the pawl 16 in either position, that is with either end 17 engaged with the teeth, a detent 19 abuts the same on opposite sides of center, such detent being slidably mounted in a tube 20 fastened to the handle and urged outwardly to the desired degree of frictional contact with the pawl 25 by an expansive coil spring 21 housed within tube 20.

35 Rotatably mounted within the main socket member 10 is an auxiliary socket member 22, the same being removable and reversible end to end, if desired. Such auxiliary socket member has bearing flanges 23 contacting the inner wall of the main socket member 10. At one end, auxiliary socket member 22 has a wrench head 24 and 40 at its opposite end it has a wrench head 25. The

head 24 is provided with a square or other socket 26 in the free end thereof, aligned with the socket 12. Head 25 also has a suitable socket 27 in the free end thereof. Each of the heads 24 and 25 has an opening 28 and 29 therethrough, 45 selectively adapted to register with openings 30 in the wall of the main socket member 10. A rod may be passed through the aligned openings 28 or 29 and openings 30 so that the socket members 10 and 22 will rotate as a unit through operation of the handle, and in either direction, according to the direction of rotation of the handle and position of the pawl 16 with respect to the teeth 13.

50 It will be realized that the wrench may be used with any of the sockets 12, 24 and 27 engaged with a nut or other part and that the socket member 22 may be reversed end to end so that either socket 27 or 26 will be exteriorly thereof.

The invention is particularly useful as in connection with dual wheels as referred to where a collar nut 31 and a cup nut 32 are removed from the wheel and applied thereto as a unit, the same being removed and applied when the hexagonal or octagonal portion of the nut 31 is engaged in the socket 12, with nut 32 outermost. After such unitary nuts have been removed, and it is desired to separate them, they may be applied in the sockets 12 and 26 as shown in the drawings. In such position, the handle may be turned and the rod or the like applied in the opening 29 may be turned relatively thereto, so as to thereby detach nut 32 from nut 31.

55 Various changes may be resorted to provided they fall within the spirit and scope of the invention.

I claim as my invention:

A tool of the class described comprising a tubular socket member adapted for turning having a socket portion in one end thereof, a removable 40 and reversible auxiliary socket member rotatable within the first mentioned socket member having socket portions in each end adapted selectively to abut the first mentioned socket portion and to align therewith, the second mentioned socket 45 portions being dissimilar, said auxiliary socket member having openings therethrough one adjacent each end, the first mentioned socket member having openings therethrough for alignment with either of the first mentioned openings, so that an element may be applied to connect the socket members for unitary rotation, said auxiliary socket member being of a length to extend beyond the first mentioned socket portion at the end opposite the socket portion to expose the 50 adjacent opening thereof for engagement by a turning element when the socket members are operated one relative to the other to detach the unitary nuts.

CHARLIE A. GRAHAM. 60
